UNITED STATES PATENT OFFICE.

KURT HEITLER, OF NEW YORK, N. Y.

JAR-LIFTER.

1,296,389.

Specification of Letters Patent. Patented Mar. 4, 1919.

Application filed November 29, 1918. Serial No. 264,545.

To all whom it may concern:

Be it known that I, KURT HEITLER, a subject of the King of England, residing at New York city, county and State of New York, have invented certain new and useful Improvements in Jar-Lifters, of which the following is a full, clear, and exact description.

This invention relates to lifters for jars and other articles, one of the objects of the invention being to provide an implement having yieldable members arranged to form a clamping device that can be inserted into a relatively deep receptacle containing jars or the like and engage the same in order to lift them out of the receptacle. The device, however, is not limited to use in connection with jars, as it is especially arranged for lifting small articles, such as eggs, potatoes, &c. To accomplish this result I have resorted to a special construction of the jaws of the lifter, the details of which I will now proceed to describe and finally claim, reference being had to the accompanying drawing, wherein—

Figure 1 is a face view of my improved lifter;

Fig. 2 is a sectional plan view thereof, enlarged, the section being taken on line 2—2 in Fig. 1;

Fig. 3 is an enlarged perspective view of one of the jaw-members;

Fig. 4 is a diagrammatic view illustrating the device engaging a small article, such as a vegetable or egg; and

Fig. 5 is a similar view illustrating the device as engaging a jar.

As herein arranged my improved lifter consists of a pair of leg-members 6 and 7, which in this instance are integral and formed intermediate the ends into a loop or coil-spring member 8^a arranged to maintain said leg-members separated; hence, when the leg-members are forced together, to engage a jar or smaller article, the loop or spring-member 8^a will be placed under an increased tension. Intermediate the ends, the leg members are offset, as at 8 and 9, to provide a relatively wide jaw 10, the members of which are indicated by 11 and 12, said members being preferably covered by a sheath of rubber, 13, or any other suitable material, to prevent the jaws from rusting and at the same time providing a better grip or hold on the articles engaged thereby.

The essential feature of my invention is

the formation of the jaw-members at the lower ends thereof to provide for the double function of grasping a relatively large article, such as a jar, or a relatively small article, such as an egg or vegetable. To accomplish this result I form the end thereof into a loop, which in this instance is triangular, the base member 14 being arcuate, which is the preferable formation. The open space 15 between the side-members 16 and 17 of the triangle allow for the passage thereinto of the ends of a relatively small article, indicated by 18 in Fig. 4. One of the advantages derived from this triangular formation is that when a small article is engaged the arcuate or base-member of the triangle can pass under the article and properly support same, as is evident from an inspection of Fig. 4, the space 15 being large enough to permit the side-members 16 and 17 to pass over the ends of the average size vegetable, egg, &c. As eggs and cooked vegetables (principally) will not stand any great amount of pressure, the peculiar formation of the jaws of my improved lifter adapts same to lift even the most delicate or tender article, as no pressure is exerted to cause the lifter to engage such articles. For lifting jars &c. the arcuate base-member 14 of the jaw is well adapted to engage the neck of jars, as indicated in Fig. 5.

For the sake of simplicity, the formation of the lower end of the jaw-members will be referred to in the claims as a loop.

As can be seen in Fig. 2 the lower corners of the triangle are offset relatively to the upper end thereof, thus providing shelf-like members or portions 19 which prevent the beading of a jar (indicated by 20 in Fig. 5) from coming in contact with the side-members of the loop, or the sheath covering same. Furthermore, this formation allows the arcuate supporting members 14 to be pressed against the neck 21 of the jar, as said arcuate member is offset or out of alignment with the side-members of the loop.

What I claim as my invention is:

1. A lifting device consisting of a pair of leg-members yieldably connected, jaw-members carried thereby at the lower ends thereof, said jaw-members being formed into a loop embodying an arcuate gripping member, said arcuate gripping member being offset with respect to the side-members of the loop.

2. A lifting device consisting of a pair of

leg-members, each of the leg-members terminating in a jaw-member bent to form a triangle to provide an open space, the base-member of the triangle being arcuate and offset with respect to the side-members of the triangle to form shelves at the lower opposite corners of the triangle.

Signed at New York city, N. Y., this 26th day of November, 1918.

KURT HEITLER.
